APPARATUS FOR REDUCING AND HOLDING
FRACTURES IN POSITION

Patrick P. Grosso, Brooklyn, N. Y.

Application May 10, 1945, Serial No. 593,020

16 Claims. (Cl. 128—84)

1

This invention relates to improvements in an apparatus for reducing and holding fractures in position, and more particularly to a mechanical splint which can be used to reduce almost any type of bone fracture, so that the device may quite properly be described as a universal fracture splint.

The objects of this invention are an ambulatory fracture splint which: substantially reduces trauma of the tissues; can be readily applied to virtually any part of the body; is adaptable to the reduction of most any type of bone fracture; is self-contained and eliminates the need for accessories; can be adjusted and readjusted in situ when necessary; and which is adapted to securely hold any bone to which it is applied without puncturing the bone, and with minimum trauma of the bone structure.

In accordance with this invention the fragments of a fractured bone are gripped crosswise of the long axis of the bone, between the points of two spaced sets of adjustable pins, which engage the bone from opposite sides thereof at spaced points preferably arranged in intersecting planes, and the pins are then moved inwards to grip or clamp the bone between the pin points with sufficient tension to permit the pins to be utilized in manipulating the bone and setting the fracture, without substantial penetration of the bone structure, whereby trauma of the bone is substantially reduced. For purposes of manipulation, each set of pins may be yoked and mounted upon a ball-socket connection for universal adjustment and said connections may in turn be mounted for compound relative movement, to vary the distance between the fractured ends of a clamped bone, to dispose the yoked sets of pins in the same or different horizontal planes, and when necessary to vary the degree of angulation between the yoked sets of pins so as to conform with any degree of angulation required, for example as at a bone joint.

In the drawings comprising four sheets of nine figures numbered Figs. 1 to 9 inclusive, certain embodiment of the invention are set forth.

Fig. 1 is a plan view of an apparatus embodying one form of the invention as applied to a fractured bone;

Fig. 2 is a side view of the apparatus only;

Figs. 3 and 4 are vertical cross sectional views taken along the lines 3—3 and 4—4 respectively of Fig. 2 looking in the direction of the arrows;

Fig. 5 is an end view of the splint with the bone and tissue shown in dotted outline;

Fig. 6 is a horizontal cross sectional view taken

2

along the line 6—6 of Fig. 2 looking in the direction of the arrows;

Figs. 7 and 8 are vertical cross sectional views taken along the line 7—7 and 8—8 respectively of Fig. 2 looking in the direction of the arrows; and

Fig. 9 is a cross sectional view of a modified form as applied to a section of a bone which is shown in dotted outline.

Like reference characters designate corresponding parts throughout the several figures of the drawings.

The invention will be better understood from Figs. 1 and 2 of the drawings which illustrate one suggested embodiment thereof. The bar 18 is longitudinally slotted to form a keyway 20 wherein a traveler 22 (Fig. 8) is longitudinally movable under control of lead-screw 19. One end of bar 18 is bent substantially at right angles and is provided with an opening forming a bearing 29 wherein one end of the lead-screw 19 is journaled. The opposite end of the lead-screw 19 is journaled in a bearing-block 32 which may be adjustably mounted adjacent the opposite end of the keyway 20. The bearing-block 32 is provided with a threaded shank 33 adapted to receive a lock-nut 34 whereby the bearing-block 32 may be securely locked in spaced relation to the bearing 29. The traveler 22 is threaded to receive the double-threaded worm of lead-screw 19. The worm is preferably provided with a left-handed thread. An operating handle 21 for operating the lead-screw 19 to move traveler 22, is mounted upon the outer end of the lead-screw 19 and is locked in position by means of a grub-screw 28. A collar 30 is mounted upon the lead-screw 19 adjacent the bearing 29, and is locked in position by a grub-screw 31. Adjacent the opposite end of lead-screw 19 an annular groove 35 is provided, and a grub-screw 36 is threadably mounted in the bearing-block 32 to engage in the annular groove 35, thus locking the lead-screw 19 against sliding movement relative to the bearing-blocks 32 and 29.

The traveler 22 (Fig. 8) is keyed in the keyway 20, and is provided with a threaded shank 83 which engages in a threaded opening in a ball-socket plate 25 of a travelling ball and socket mounting 23. The socket-plate 25 is adapted to receive the ball portion 24 of an L-shaped bracket 61. The ball and socket mounting 23 may be U-shaped or otherwise formed for attachment to the socket-plate 25. The ball-socket mounting 23 is female threaded to accommodate the locking-screw 26 which engages the ball 24 to lock the universal joint in any selected position. The

locking-screw 26 may be manipulated in any preferred manner as by means of the operating handle 27.

The saddle plate 84 (Fig. 8) is provided with an opening to receive the threaded shank 83 of the traveler 22. This opening may be female threaded to register with the threads of shank 83. Saddle plate 84 is substantially C-shaped in cross section (Fig. 8) to hook around the edges of the bar 18, thereby securing traveler 22 and ball socket 23 and the travelling ball and socket mounting 23 against lateral movement.

The rotatable extension piece 39 is pivotally connected to the end of the bar 18 by means of a suitable nut and bolt 37; whereby the rotatable extension piece 39 may be swung about the pivot 31 into and out of longitudinal alignment with the longitudinal axis of the bar 18. A threaded wing bolt 38 is adjustably mounted in the rotatable extension piece 39 to engage the lower face of the bar 18, thereby locking extension piece 39 in alignment with, or in correct position of angulation relative to, the bar 18.

The extension piece 39 is substantially U-shaped, the intermediate section of extension piece 39 being provided with a slotted keyway 44 (Fig. 4), adapted to receive a vertical traveler 43. The traveler 43 is provided with a tenon (Fig. 6), which is adapted to register in slotted keyway 44. The tenon portion of traveler 43 terminates in a threaded shank 48 furnished with a lock nut 49. Traveler 43 is threadably mounted upon the double left-hand threaded worm of lead-screw 40 which is journaled to rotate in upper and lower bearings 41 and 45. The button head of a retaining screw 42 engages against the shoulder of the upper bearing 41 to secure lead-screw 40 in place. Lead-screw 40 may be manipulated in any preferred manner, as by means of the butterfly handle 47 which may be attached to the lead-screw 40 by a grub-screw 46.

An adjustable bracket 52 is provided with an opening adapted to receive the threaded shank 48 of the vertical traveler 43, the adjustable bracket 52 being locked to the threaded shank 48 by the lock-nut 49 so that the adjustable bracket 52 may be raised or lowered with the traveler 43 relative to the extension piece 39. The intermediate portion of extension piece 39 may be provided with a guideway 50 (Fig. 6) having shoulders 51-51. The guideway 50 and shoulders 51-51 co-operate to insure proper vertical alignment of the adjustable bracket 52 relative to the extension piece 39 (compare Figs. 2, 3 and 6).

The adjustable bracket 52 is extended to form a socket-plate 55 carrying a yoke 57 which is secured to the adjustable bracket 52 in any suitable manner as by means of the screws 80-80 (Fig. 5). The ball 54 is seatable in the socket-plate 55 to form a universal ball and socket connection for the L-shaped bracket 61 which forms a continuation of the neck 60 of the ball 54. The yoke 57 is female threaded to receive the locking screw 56 which is adapted to engage the ball 54 and lock the ball and socket connection in any predetermined position. The locking screw 56 may be manipulated in any suitable manner as by means of the operating handle 58. The surface of the ball 54 may be milled or burred at 59 to increase friction with the locking-screw 56. The end of locking-screw 56 may be made concave to conform to the contour of ball 54, and may be milled or burred to increase friction with the ball 54. The socket-plate 55 may form an in-

tegral part of the adjustable bracket 52, or it may be a separate element adapted to be attached to the bracket 52 in any preferred manner as by means of the screws 53-53 (Fig. 1).

By this construction the L-shaped bracket 61 carried by the universal ball and socket joint 24-25, and the L-shaped bracket 61 carried by the universal ball and socket joint 54-55, may be relatively adjusted in a variety of ways as follows: (a) by proper manipulation about the pivot 31 and of the vertical traveler 43 they may be placed in horizontal and vertical alignment; (b) by manipulation of the traveler 22 under control of the lead-screw 19 and operating handle 21 they may be disposed in varying spaced relation; (c) by manipulation of the vertical traveler 43 under control of the lead-screw 40 and butterfly handle 47 they may be variously disposed in different horizontal planes; and (d) by manipulation of their respective universal ball and socket joints 24-25, 54-55 they may be disposed at any desired angle relative to each other.

Each L-shaped bracket 61 constitutes a separate holder for a pair of adjustable braces 64 and 65, which braces in conjunction define a bifurcated yoke for supporting a plurality of pairs of adjustable bone pins 75-75 and 79-79 (Figs. 1 and 5). The pins 75 and 79 are adapted to engage the structure of a bone without puncturing it.

Each L-shaped bracket 61 (Figs. 7 and 8) is provided with a threaded stud 61 and one or more positioning studs 62-62. The braces 64 and 65, which are substantially L-shaped, are provided with a plurality of adjustment holes 63, 63 and 69-69 which are large enough to register with the threaded stud 61 and the positioning studs 62-62. The braces 64 and 65 are respectively tongued and grooved to register with each other (see Fig. 7). These several features of construction facilitate the assembly of the parts, so that when the adjustment holes in one of the braces, as, for example, the adjustment holes 69 in the tongued brace 64, are brought into co-operative registry with the threaded stud 61 and the positioning studs 62-62 of the L-shaped bracket 61, and one of the adjustment holes 63 of the grooved brace 65 is thereafter brought into co-operative registry with the threaded stud 61, the tongue of the brace 64 registers in the groove of the brace 65, and by manipulation of the wing-nut 60 which is threadably mounted upon the threaded stud 61 the two braces may be locked together. The shoulder 63 of the L-shaped bracket 61 (Fig. 7) tends to retain the tongued brace 64 in correct transverse alignment. By this general arrangement the wing-plates 70-70 of the braces 64 and 65 (Fig. 5) may be adjustably separated to form a yoke or clamp of any desired width dependent upon the size of the particular limb or part of the body to which the universal fracture splint is intended to be applied. Each brace 64 and 65 supports a threaded stud 74 suitably anchored to its wing-plate 70. Each wing-plate 70 forms a suitable support for a pair of bone pins which are slidably adjustable towards and away from each other so as to penetrate the tissue and engage the bone structure at four spaced points located in intersecting planes. The points of the pins engage the bone, but do not penetrate the bone substantially.

Referring particularly to Figs. 1 and 5, the wing-plate 70 of brace 64 supports a vertical yoke 78 having two vertically spaced bone pins

79-79. The wing-plate 70 of the brace 65 supports a horizontal guide plate 71 which is provided with spaced openings forming guideways for the horizontally spaced bone pins 75-75 secured to the horizontal yoke 74. The horizontal yoke 74 and the vertical yoke 78 and the bone pins 75-75 and 79-79 carried by the respective yokes, may be adjusted in and out by the manipulation of their respective wing-nuts 72-72. Each wing-nut 72 is provided with an annular groove 76 adapted to receive a bifurcated follower 73 suitably anchored to one of the yokes 74 or 78. In this manner the manipulation of the wing-nut 72 causes the bifurcated follower 73 to slide the yoke 74 or 78 as the case may be, towards and away from its wing-plate 70, thereby increasing or decreasing the depth of penetration of the bone pins 75-75 or 79-79 in the tissue until the points of the bone pins engage the bone at four spaced points without however penetrating the bone substantially, and without puncturing the bone structure, the bone pins being arranged in intersecting planes upon opposite sides of the bone, whereby said bone is tightly clamped with minimum trauma between the points of the bone pins, against movement in any direction.

Thus after one end of a fractured bone has been clamped at four spaced points between one set of pins 75-75 and 79-79, and the other end of a fractured bone has been similarly clamped between the other set of bone pins 75-75 and 79-79 at four spaced points, the ball and socket joints 24-25 and 54-55 may be adjusted and locked at any desired angle relative to their respective mountings 23 and 57 and thereafter adjusted and locked by means of pivot 37 and wing bolt 38 either in longitudinal axial alignment or in any other desired position, by thumb-pressure on the butterfly handle 47 the bracket 52 may be raised or lowered relative to the bar 18, and by operating the handle 21 the spacing between the two sets of bone pins may be varied at will to increase or decrease the distance therebetween, thus retracting the fractured portions of the bone until the ends of the fractured bone are brought into the correct position for reduction of the fracture, whereupon the splint as adjusted and locked, may be retained in position as an ambulatory splint until the fracture is properly healed. In this manner the immobilization of the injured member may frequently be entirely eliminated.

The device may also be used for treating and correcting deformities of the bones, ankylosis, joint fixation, and in bone-grafting surgery. It is especially of value in those cases where a fracture requires traction for a period of time before reduction can be accomplished, as well as in those cases where manipulation of the bones is required. In those cases where an X-ray or a fluoroscopic examination discloses that reduction is not perfectly satisfactory, the locking screws may, if necessary, be loosened, the fracture manipulated, the splint readjusted in situ, and tension again applied to the locking screws.

The pins 75-75, 79-79 penetrate the body tissue 14, and the points engage the fractured pieces 15-16 of the bone upon opposite sides of the fracture line 17, to clamp the fractured pieces 15-16 of the bone between the pins 75-79 by pressure applied at spaced points arranged in intersecting planes. This is accomplished without puncturing the bone, and with minimum trauma of the tissue 14 and of the bone structure.

Fig. 9 shows a modified form of the brace, and of the ball-socket assembly. The base plate 81 and screws 82 replace the yoke 57 and screws 80.

The tongued and grooved braces 64 and 65 which make up the adjustable bifurcated yokes may also be replaced by the bifurcated yokes 85. Each yoke 85 is made in one single piece in the general form of a horse-shoe, and is provided with a curved slot 86 for receiving one or more threaded studs 67 whereby the yoke is rockably adjustable in the curved track 88 which is formed in the curved brackets 87. The curved bracket 87 is in turn mounted upon the ball and socket joint 24-25 (or 54-55). The curved overhanging shoulder 89 of the bracket 87 engages the curved brace 85 and aligns it in the track 88. One or more wing-nuts 66 lock the brace 85 in the desired position relative to the curved bracket 87.

The universal splint may also be constructed in different sizes, for example three—small, medium, and large, equipped with bifurcated yokes and bone pins 75-75 and 79-79 of different sizes, dependent upon the size of the splint or the character of the use for which it is designed. This modified form of the device provides a universal kit with the splints graduated as to size, weight and strength according to the intended use.

In practising the method, the braces are adjusted to straddle the fractured limb above and below the point of fracture 17. The bone pins 75-75 and 79-79 are then inserted through the tissue 14 from opposite sides of each of the bone fragments 15 and 16 and crosswise the long axis 35 of the bone, until the bone pins engage the bone structure at spaced points preferably arranged in intersecting planes. By rotating the winged nuts 72-72 the bone pins 75-75 and 79-79 move towards each other until the bone fragment 15 (or 16) is gripped between the points of the bone pins with sufficient tension to hold the bone securely. The bone pins 75-75 and 79-79 and their associated braces or pin carriers may now be utilized preferably as a part of the mechanical splint, to retract the bone fragments 15 and 16 and bring their fractured ends into alignment or setting position, whereupon the bone is set. Trauma of the tissues is substantially reduced, and since the points of the pins 75-75 and 79-79 penetrate the bone structure but slightly without puncturing it, trauma of the bone is substantially reduced.

The splint is a self-contained unit, which can be fitted without the use of wrenches, drills, extra pins, or any other accessories. It can be readily disassembled, cleaned, sterilized, and reassembled ready for further use.

Other modifications will be obvious to those skilled in the art.

60 What is claimed is:

1. A fracture splint comprising a plurality of pin carriers, a bar comprising a plurality of sections pivotally connected together, said pin carriers being spacedly mounted upon said bar sections with ball and socket connections, means for varying the horizontal distance between said pin carriers, and means for varying the relative level of the pin carriers, each of said pin carriers carrying oppositely disposed sets of pins with the ends of one set directed towards the ends of the other set but located in mutually intersecting planes.

2. A fracture splint comprising a bar, said bar comprising two end sections with an intermediate section therebetween, a pivotal connection be-

tween said intermediate section and one end section, a vertically disposed slide and guide connection between said intermediate section and the other end section, a plurality of pin carriers, ball and socket connections between said pin carriers and the end sections of said bar, a lead-screw for moving one of said pin carriers along its associated end section, and a lead screw for raising and lowering the other end section and its associated pin carrier relative to the intermediate section, each of said pin carriers carrying oppositely disposed sets of pins with the ends of one set directed towards the ends of the other set but located in mutually intersecting planes.

3. A fracture splint comprising a bar, said bar including two end sections and an intermediate section, a pivotal connection between said intermediate section and one end section, a vertically disposed slide and guide connection between said intermediate section and the other end section, a pair of pin carriers, each of said pin carriers being adjustable to different widths, ball and socket connections between said pin carriers and the end sections of said bar, a lead screw for moving one of said pin carriers along its associated end section, and a lead screw for raising and lowering the other end section and its associated pin carrier relative to the intermediate section, each of said pin carriers carrying oppositely disposed sets of pins with the ends of one set directed towards the ends of the other set but located in mutually intersecting planes.

4. A fracture splint comprising a bar, said bar including two end sections, a pair of pin carriers, each pin carrier being adjustable to varying widths, universal joints for attaching said pin carriers to the end sections of said bar in spaced relation, a set of pins adjustably supported by each pin carrier and with the sets directed towards each other in mutually perpendicular planes, said pins being sharpened to penetrate tissue and engage opposite sides of a bone at a plurality of points spaced crosswise to clamp the bone without substantial trauma thereof, and means for moving said pin carriers into and out of parallelism and for varying the horizontal distance between said pin carriers.

5. A fracture splint comprising a bar, said bar including two end sections and an intermediate section, a pivotal connection between said intermediate section and one of the end sections, a pair of pin carriers, each pin carrier being adjustable to varying widths, universal joints for attaching said pin carriers to the end sections of said bar in spaced relation, a set of pins adjustably supported by each pin carrier and with the sets directed towards each other in mutually perpendicular planes, said pins being sharpened to penetrate tissue and engage and clamp a bone from opposite sides without substantial trauma thereof, and means for moving said pin carriers into and out of parallelism and for varying the horizontal distance between said pin carriers.

6. A fracture splint comprising a bar, said bar including two end sections, a pair of pin carriers, each pin carrier being adjustable to varying widths, universal joints for attaching said pin carriers to the end sections of said bar in spaced relation, a set of pins adjustably supported by each pin carrier and with the sets directed towards each other in mutually perpendicular planes, said pins being sharpened to penetrate tissue and engage opposite sides of a bone at a plurality of points spaced crosswise to clamp the bone without substantial trauma thereof.

means for regulating the depth of penetration of, and the clamping pressure exerted by, the pins, and means for raising and lowering one of said pin carriers relative to the other and for varying the horizontal distance separating said pin carriers.

7. A fracture splint comprising a bar, said bar including two end sections and an intermediate section, a pivotal connection between said intermediate section and one of the end sections, a pair of pin carriers, each pin carrier being adjustable to varying widths, universal joints for attaching said pin carriers to the end sections of said bar in spaced relation, a set of pins adjustably supported by each pin carrier and with the sets directed towards each other in mutually perpendicular planes, said pins being sharpened to penetrate tissue and engage and clamp a bone between said pins at a plurality of spaced points without substantial trauma of the bone, means for regulating the depth of penetration of, and the clamping pressure exerted by, the pins, and means for raising and lowering one of said pin carriers relative to the other and for varying the horizontal distance separating said pin carriers.

8. A fracture splint comprising a bar, said bar including two end sections, a pair of pin carriers, each pin carrier being adjustable to varying widths, universal joints for attaching said pin carriers to the end sections of said bar in spaced relation, a set of pins adjustably supported by each pin carrier and with the sets directed toward each other in mutually perpendicular planes, said pins being sharpened to penetrate tissue and engage opposite sides of a bone at a plurality of points spaced crosswise to clamp the bone without substantial trauma thereof, means including lead-screws for regulating the depth of penetration of, and the clamping pressure exerted by, the pins, and means including lead-screws for moving said pin carriers to vary the horizontal and the vertical distance between said sets of adjustable pins.

9. A fracture splint comprising an L-shaped bar having keyways extending along its longitudinal and vertical arms, travellers associated with and movable along each of said keyways, lead-screws associated with each of said travellers for regulating the direction and extent of their movement along their respective keyways, and pin carriers rockably mounted on said travellers.

10. A fracture splint comprising an L-shaped bar having keyways extending along each arm thereof, travellers associated with and movable along each of said keyways, lead-screws associated with each of said travellers for regulating the direction and extent of their movement along their respective keyways, pin carriers rockably mounted on said travellers, a set of pins adjustably supported by each pin carrier, said pins being sharpened to penetrate tissue and engage a bone at four spaced points thereby clamping the bone without substantial trauma thereof, and means for regulating the depth of penetration of, and the degree of clamping pressure exerted by, the pins.

11. A fracture splint comprising a pin carrier, and a plurality of sets of oppositely disposed pins supported by the carrier, said pins being pointed and mounted in mutually intersecting planes with the points of the pins of one set facing inwards towards the pins of the other set to penetrate tissue and engage points spaced crosswise of a

bone from opposite sides to clamp the bone without substantial trauma.

12. A fracture splint comprising a forked brace, a plurality of pins slidably mounted adjacent the forked ends of the brace, said pins being pointed and aligned in intersecting planes with the points of the pins facing inwards, so that when the forked portion of the brace straddles the tissue about the fractured bone the pins may be moved inwards to penetrate the tissue and engage spaced points of the bone from opposite sides thereof to clamp the bone without substantial trauma thereof, means operable to regulate the extent of penetration of the pins mounted on one side of the forked brace, and means operable to regulate the extent of penetration of the pins mounted on the other side of the forked brace.

13. A fracture splint comprising a pin carrier, and oppositely disposed pairs of pins with the pins of one set mounted in a transverse plane with respect to the pins of the opposite set, means for adjustably mounting the pairs of pins for movement towards and away from each other while maintaining them in intersecting planes to penetrate the tissues and immobilize a section of bone when engaged between said pairs of pins without puncturing the bone or substantial trauma thereof.

14. A fracture splint comprising a pin carrier, oppositely disposed pairs of pins with the pins of one set mounted in a plane which intersects the plane of the other set, means for mounting said pairs of pins for movement towards and away from each other while maintaining them in intersecting planes to penetrate the tissues and immobilize a section of bone when engaged between said pairs of pins without puncturing or substantial trauma of the bone, and means for adjusting the depth of penetration of the pairs of pins to engage and immobilize the bone.

15. A fracture splint comprising an adjustable pin carrier, oppositely disposed pairs of pins with the pins of one set mounted in a plane which intersects the plane of the other set, means for

mounting said pairs of pins for movement towards and away from each other while maintaining them in intersecting planes to penetrate the tissues and immobilize a section of bone when engaged between said pins without puncturing the bone or substantial trauma thereof, and means for adjusting the depth of penetration of the pins to engage and immobilize the bone.

16. A fracture splint comprising a plurality of pin carriers individually adjustable for width, oppositely disposed pairs of pins supported by each of said carriers, means for mounting said pairs of pins on said carriers in mutually intersecting planes, means for effecting movement of said pairs of pins towards and away from each other to penetrate the tissues and engage opposite sides of a section of fractured bone at four spaced points to immobilize said bone when so engaged without puncturing or substantial trauma of the bone, two of the said points lying along the long axis of a bone and the other two upon opposite sides of the said axis, said pin carriers being relatively adjustable in the same longitudinal plane into and out of parallel longitudinal planes and into and out of angularly disposed planes, and means operable to impart said relative adjustments to said pin carriers.
